Kristoffer Jensen Nordby,
By *Henry Orth* atty.

UNITED STATES PATENT OFFICE.

KRISTOFFER JENSEN NORDBY, OF LIER, NORWAY.

DITCH-DIGGING MACHINE.

1,374,093.

Specification of Letters Patent.

Patented Apr. 5, 1921.

Application filed January 6, 1920. Serial No. 349,796.

To all whom it may concern:

Be it known that I, KRISTOFFER JENSEN NORDBY, a subject of the King of Norway, residing at Lier, Norway, have invented 5 certain new and useful Improvements in Ditch-Digging Machines; and I do hereby declare the following to be a full, clear, and exact description of the invention, such as will enable others skilled in the art to which 10 it appertains to make and use the same, reference being had to the accompanying drawings, and to letters or figures of reference marked thereon, which form a part of this specification.

15 This invention relates to the type of ditch digging machines, the digging apparatus of which comprises an oscillating substantially vertical beam provided with teeth or diggers working on the end face of the ditch.

20 In the machines of this kind it has been found to be of considerable importance, that the curves described by the diggers are in such relation to the ditch wall that shocks in the longitudinal direction of the 25 machine are avoided as far as possible. This is obtained according to the present invention by means of a guiding mechanism for the oscillating beam giving the same such a movement that the radii of curvature 30 for the curves described by the several diggers have their maximum at the parts of the curves on which the diggers are working.

The invention also comprises means for 35 facilitating the removal of gravel from the digging apparatus, and the subsequent conveying of the gravel from the beam of the ditch to the ground.

On the drawing Figure 1 is a side view 40 of the rear part of the machine showing the digging apparatus.

Fig. 2 is a detail of the conveyer.

The digging machine comprises as usual 45 an oscillating vertical beam 1 driven by means of crank 2 and guided in slot 3. Said slot 3 is so formed and placed with regard to crank 2, that the diggers 4 describe the egglike curves indicated in dotted lines, the upper curves having their longitudinal axes 50 more or less vertical, while the lower curves have their axes in a more or less horizontal position, the parts of the curves having the largest radii of curvature being always adjacent the wall of the ditch.

55 By means of the oscillating beam the gravel is loosened and thrown backward

where it is taken up by the elevator. The elevator comprises a plurality of flat plates 5 constituting links (Fig. 2) each having two eyes 5^a formed on one end, and two 60 eyes 5^b formed on the other end thereof, the axes of said eyes being in substantially the plane of the plates. The eyes 5^a are so spaced apart that when two plates 5 are placed end to end said eyes 5^a will lie between the inner edges of the eyes 5^b, and the plates are connected together by a bolt or pin 6 passing through both pairs of eyes as shown in Fig. 2, thus forming a hinged connection. Each plate 5 is formed with 70 two longitudinal parallel slots 7 forming a central portion 8 which is shorter than the sides of the plate, thus leaving a space or transverse slot 7^a between one end of the said central portion and the eyes, 5^a and 5^b. 75 A bucket 9, of the form shown in Fig. 1, consists of two sides 9^a, a curved end 9^b and a bottom portion 10 having an integral sleeve 10^a formed on one end adapted to fit between the inner edges of the eyes 5^a and 5^b through which the pin 6 passes forming a pivot for the bucket, the sides 9^a and end 9^b of the latter normally extending through the slots 7 and 7^a respectively.

The central part 8 of the plate links fit 85 into the elevator buckets 9, and in their normal position lie flat against the bottom 10 of the same. The bottom 10 of the elevator buckets 9 is provided with lateral lugs 11 adapted to be engaged by a curved guide 90 12 by means of which the buckets are swung back, as indicated in Fig. 1. By this movement the remaining contents of the bucket are removed from the same by means of plate 9, which remains in its original position, and the exterior surface of which is scraped clean by means of stationary scraper 13.

The carriage frame 14 is mounted on a front axle (not shown) and on a rear 100 axle 17.

Claims:

1. An elevator for excavators and the like, comprising an endless carrier consisting of a plurality of articulated flat plates 105 each having a transverse slot and longitudinal slots formed therein, and a pair of connecting eyes on opposite ends, the eyes on one end of each plate adapted to lie between the eyes on the opposite end of an 110 adjoining plate, a bucket having a connecting sleeve on one end adapted to fit between

both pairs of eyes of adjoining plates, a pin passing through said eyes and sleeve forming a hinge connection therefor, and an end and sides formed on said bucket adapted to normally extend through the slots in the plates.

2. An elevator for excavators and the like, comprising an endless carrier consisting of a plurality of articulated flat plates 10 each having a transverse slot and longitudinal slots formed therein and a pair of connecting eyes on opposite ends, the eyes on one end of each plate adapted to lie between the eyes on the opposite end of an adjoining plate, a bucket having a connecting sleeve on one end adapted to fit between

both pairs of eyes of adjoining plates, a pin passing through said eyes and sleeve forming a hinge connection therefor, an end and sides formed on said bucket adapted to normally extend through the slots in the plates, means for operating the elevator, a stationary guide, and lugs on the buckets engaged by the latter for withdrawing the buckets from said slots.

25 In testimony that I claim the foregoing as my invention, I have signed my name in presence of two subscribing witnesses.

KRISTOFFER JENSEN NORDBY.
